(57) **CLAIM**

The ornamental design for a cosmetic spatula, as shown and described.

DESCRIPTION

1. Cosmetic spatula

1.1 : Perspective

1.2 : Front

1.3 : Back

1.4 : Left

1.5 : Right

1.6 : Top

1.7 : Bottom

The product of the design is used for taking cosmetics out of the container or for spreading cosmetics to skin such as the face; the characteristic features of the design lie in the shape; one of the drawings which best characterizes the main point of the design is a perspective view.

1 Claim, 7 Drawing Sheets
